UNITED STATES PATENT OFFICE

ARTHUR T. CARNEY, OF BLAIRSVILLE, PENNSYLVANIA, ASSIGNOR OF ONE-THIRD TO
R. E. MILES, JR., OF WILKINSBURG, PENNSYLVANIA

DESIGN FOR A RADIOCABINET

Application filed April 20, 1932. Serial No. 43,556. Term of patent 14 years.

To all whom it may concern:

Be it known that I, ARTHUR T. CARNEY, a citizen of the United States, residing at Blairsville, in the county of Indiana and State of Pennsylvania, have invented a new, original, and ornamental Design for a Radio Cabinet, of which the following is a specification, reference being had to the accompanying drawing, forming part thereof, in which drawing the figure is a perspective view of the radio cabinet, showing my new design.

The cabinet is flat at the rear portion thereof, the rear port on being adapted to be placed against the wall as is the custom in such radio cabinets.

I claim:

The ornamental design for a radio cabinet, as shown and described.

Signed at Blairsville, in the county of Indiana and State of Pennsylvania, this 4th day of April, 1932.

ARTHUR T. CARNEY.
